UNITED STATES PATENT OFFICE.

JAMES T. KEYES, OF NEW YORK, N. Y.

SIDE GUARD FOR SPRING-MATTRESSES.

1,045,563.

Specification of Letters Patent. Patented Nov. 26, 1912.

Application filed September 17, 1912. Serial No. 720,758.

To all whom it may concern:

Be it known that I, JAMES T. KEYES, a citizen of the United States, residing in the borough of Manhattan, city of New York, 5 State of New York, have invented new and useful Improvements in Side Guards for Spring-Mattresses, of which the following is a specification.

My invention relates to wire mattresses, 10 and has for its object to provide in the same an improved form of side guard for preventing the shifting or spreading of the hair or other stuffed mattress supported thereby.

More specifically my improvement consists in constructing said side guards so that 15 they may be either folded or otherwise shifted out of the way for transportation, and yet may be readily positioned for use.

In the accompanying drawing: Figure 1 20 is a perspective view of my improved wire mattress with the side guard in position for use. Fig. 2 is a fragmentary end elevation showing the side guard in one of its folded positions. Fig. 3 is a detail transverse sectional view, showing in full lines the side 25 guard in operative position, and in dotted lines the same in another folded position. Fig. 4 is a view similar to Fig. 3, partly broken away, illustrating a modified construction.

Similar numerals of reference denote corresponding parts in the several views.

In the said drawing the reference numeral 1 denotes a woven wire mattress body of any 35 approved construction, the free longitudinal edges of which are suitably thickened or reinforced, as shown at 2. This mattress is fixed in the usual manner upon the supporting frame comprising transverse end bars 3, 40 to which the mattress 1 is permanently attached as shown, and the side bars 4, and is of sufficient width to project at each side beyond said side bars 4 a distance to constitute the side guards 5. At each end of the frame 45 is attached one leaf of an ordinary hinge 7, the other leaf 8 of which has fixed thereto the ends of the side guards 5, the same being clamped by means of a plate 9 preferably riveted to leaf 8, as shown in Fig. 3. It will 50 be seen that by means of this hinged connection between the ends of the side guards 5 and the spring mattress 1, said guards may be readily positioned for use, as shown in Fig. 1, or may be folded out of the way for 55 transportation or storage in either the manner shown in Fig. 2, wherein said guard is

folded down against the side bar 4, or in the manner shown in dotted lines in Fig. 3, wherein said guard is folded inward upon the spring mattress 1. While the normal 60 longitudinal tension exerted upon the spring mattress 1 and side guards 5 will usually be sufficient to maintain said side guards in any adjusted position, still I contemplate employing any suitable fastening means, 65 such as the links 10, connected at their ends with the outer ends of side guards 5, and slotted at 11 near their other ends to be engaged by set nuts 12 for fastening said links in any adjusted position. While I have 70 shown, in Figs. 1, 2 and 3, the side guards 5 formed integral with the wire mattress 1, I do not wish to limit myself to such construction, and have shown in Fig. 4 a modification wherein said side guard and wire mattress 75 are entirely distinct. Thus the side guard is made up of a section of woven wire 13 stretched between longitudinal bars 14, the same being entirely independent of the spring mattress, and being pivotally 80 supported from the frame of the latter by means of bars 15 pivoted at 16 to said frame and at 17 to the side guard, said guard being thus capable of movement bodily vertically into operative position, as 85 shown in dotted lines, Fig. 4, or to inoperative or transportation position, as shown in full lines, Fig. 4. And, if desired, I may employ in connection with the pivots 16 set nuts 18 for clamping said bars 15 in any 90 adjusted position, or may employ any other suitable means for retaining said bars.

Having thus described my invention, what I claim as new and desire to secure by Letters Patent is:

1. In combination with a wire mattress body and its frame, a side guard, connections therebetween whereby said guard may be adjusted to operative position, or shifted in close relation to said mattress body and frame for transportation or storage, and means for locking said guard in any adjusted position.

2. In combination with a wire mattress and its frame, a side guard, and hinges connecting said guard and frame for permitting the adjustment of said guard to operative position or for shifting said guard either inwardly into contact with said mattress or downwardly into contact with said frame.

3. In combination with a wire mattress

and its frame, a side guard, hinges connecting said guard and frame for permitting the adjustment of said guard to operative position or for shifting said guard either inwardly into contact with said mattress or downwardly into contact with said frame, and means for locking said guard in any adjusted position.

In testimony whereof, I have hereunto set my hand in the presence of two subscribing witnesses.

JAMES T. KEYES.
